METHOD AND APPARATUS FOR DISPENSING LIQUEFIED GASES

Filed May 20, 1943

FIG. 1

UNITED STATES PATENT OFFICE

2,368,215

METHOD AND APPARATUS FOR DISPENSING LIQUEFIED GASES

Odd A. Hansen, Kenmore, N. Y., assignor to The Linde Air Products Company, New York, N. Y., a corporation of Ohio

Application May 20, 1943, Serial No. 487,793

9 Claims. (Cl. 62—1)

The invention is concerned with the storage and dispensation of liquefied gases, and is particularly directed to the transfer of charges of the material from a transport or main storage container to a second container which serves as the immediate source of supply of the material for industrial uses and which accordingly has associated therewith means for withdrawing the material as required and vaporizing it and heating the gases to a condition suitable for such use. Liquids of the character to which the invention is applicable are highly volatile, having a boiling point at atmospheric pressure below 273° K. The invention is particularly useful in the handling and dispensing of liquid oxygen, the boiling point of which at atmospheric pressure is in the range below 233° K.

An economical means of rendering the material available as required for use is to provide a moderate size container, commonly referred to as a "converter," in which a supply of the material is maintained under a pressure equal at least to the service pressure required, the material being primarily in the liquid phase but being present also in the gas phase in the container space immediately over the liquid contents. Such an arrangement requires, of course, intermittent recharging of the converter, and the present invention is concerned with the recharging methods.

The highly volatile character of the liquid handled and the extremely low temperature thereof, together with the desirability of avoiding losses of the material and avoiding also any substantial interruption in the service to the consuming apparatus introduces difficulties and problems not exhibited in the handling of ordinary liquids. If upon a recharging operation the container is maintained otherwise completely closed the gas space is progressively reduced in volume, with corresponding compression of the gas present. This usually would result in an excessive pressure, although not necessarily so since the condition is affected by the refrigerating characteristics of the liquid, and also the raising of the boiling point under increased pressure may in itself result in some liquefaction of the compressed gases. Heat leakage into the container adds another uncertain and variable factor.

The present invention is adapted to meet these conditions and to take advantage in fact of the refrigeration capacity of the added liquid. In accordance with the method thereof the recharging is accomplished in a manner to control the pressure in the container by the effect of the added liquid, and the pressure may be main-

tained substantially constant at any selected value, such as that desired for supplying the material for its customary industrial uses. A particular feature is an arrangement and method 5 of operation whereby the recharging liquid is selectively delivered directly either to the liquid phase or the gas phase of the container. The effect of such selective delivery is that when the added liquid is delivered to the liquid phase relatively little change in heat content of the gas in the space over the liquid occurs during the recharging operation and, accordingly, the reduction in the gas volume results in progressively increased pressure which may rise to undesirable 10 and dangerous values; but if the liquid is delivered to and through the gas space the added liquid, because of the pressure exerted thereon in forcing it into the receiver, will be subcooled and the refrigeration contained therein will serve to 15 condense part of the gas in the container, correspondingly reducing the pressure thereof. By selective delivery to the gas and liquid phase the pressure in the receiving container may be maintained substantially constant at a predetermined 20 value.

Other objects of the invention will in part be obvious and will in part appear hereinafter.

The invention accordingly comprises the several steps and the relation of one or more of 30 such steps with respect to each of the others, and the apparatus embodying features of construction, combinations of elements and arrangement of parts which are adapted to effect such steps, all as exemplified in the following detailed description, and the scope of which invention will be 35 indicated in the claims.

For a fuller understanding of the nature and objects of the invention reference should be had to the following detailed description taken in 40 connection with the accompanying drawing, in which:

Fig. 1 is a view partly in section and partly in elevation showing a system for transferring liquid oxygen from a portable container to a receiving 45 container in accordance with the invention; and

Fig. 2 is a view partly in elevation and partly in section taken on the line 2—2 of Fig. 1 showing in general an arrangement of a rotary pump with driving means therefor which may be used in the 50 combination of Fig. 1.

The system depicted in Fig. 1 in its general layout corresponds to that of my copending application, Serial No. 403,935, filed July 25, 1941, of which the present application is a continuation in part. The main supply source may be either

a large stationary storage container, or, as particularly shown, a transport container.

Referring now to the drawing and particularly to Fig. 1, 10 denotes a wheeled chassis of a motor vehicle powered by suitable means, such as an internal combustion motor. Such chassis here supports a transport container, shown as comprising a casing 11 and a liquid holding vessel 12, the casing being spaced from the vessel 12, in order to provide a suitable space 13 for insulating purposes, for example, one which may be filled with powdered insulating material, such as magnesium carbonate. The container 12 may, if desired, be thick-walled so as to withstand high pressures. The container 12 is also shown provided with a closable vent 14.

Associated with the transport container is a suitable liquid transferring means which may comprise a mechanical pumping device, such as a turbine pump 15, having one or more stages, depending on the kind of service it is required to give. The pump is provided with suitable driving means, for example, an electric motor, shown at M in Fig. 2. The power for such motor is had from any convenient source, as from a power line run from an outlet or plug-in receptacle at the consuming installation. It is also contemplated using a power take-off on the torque shaft of the motor vehicle as the source of driving power, as set forth in my copending application, Serial No. 369,023, filed December 7, 1940.

The pump 15 has a liquid supply connection 16 connected to withdraw liquid from a point substantially at the bottom of the vessel 12 and convey it to the inlet of pump 15. A connection 18 is also provided and arranged to convey away the discharge from the outlet of the pump; a flexible portion 18' being attached by means of a suitable coupling. Suitable conduits and controls are provided to enable the liquid to be delivered selectively either to the liquid or gas phase of the receiver container. To this end the delivery line 18 divides into two branches 19 and 19' respectively. The branch 19' also has in shunt therewith a conduit 19''. The control and operation of these lines will be described later.

The liquid receiving or storage container is designated 20 and comprises part of a system arranged to supply the consuming apparatus with gaseous or vaporized liquid oxygen under a desired pressure. The pressure vessel 20 here employed preferably has a spaced inner basket 21 for holding the liquid, and reducing the amount of heat otherwise transferred thereto by conduction. The wall of vessel 20 is made sufficiently thick to withstand the operating pressure, for example, a pressure of 150 lbs. per square inch gauge. The vessel 20 is connected to discharge into suitable heating and liquid vaporizing devices which are operatively associated therewith, the arrangement comprising a so-called "cold converter system." Such connections are shown as comprising a gas phase withdrawal connection 24 leading from the gas space of the vessel 20 and discharging into a heating coil 25 from which the heated gas passes to a consuming device. Connection 24 is provided with a shut-off valve such as shown at 24'.

A liquid phase withdrawal connection 26 is also provided, which leads from a point relatively close to the bottom of the liquid holding vessel 12 and discharges into a heating coil 27. This line also has a shut-off valve as shown at 75

26'. The discharge from the coil 27 is led through a reentrant connection 28 which traverses a liquid column or side conduit 29 that is adjacent vessel 20; an automatic flow controller, such as the regulator shown at 23, being preferably introduced in connection 28 at a suitable point. The conduit 29 is connected to the interior of vessel 20, or more exactly to that of the basket 21, at its ends at points both above and below the normal liquid level in the manner taught in United States Letters Patent No. 1,950,353, issued in the name of L. I. Dana on March 6, 1934. The liquid in the column becomes heated and serves to accelerate the withdrawal of liquid from the container and to hasten the vaporization of oxygen in the cold converter system. The connection 28 leads out again to the exterior of the container to a place of use and preferably includes another heating coil 30.

Suitable heating media are supplied for heating the coils 25, 27, and 30, comprising the three heating means here associated with the receiving container and denoted generally at H.

To achieve priming of the pump 15, a connection 31 having a valve 32 is provided and arranged to lead from the outlet of the pump to the gas space of the vessel 12.

The branch 19 of the discharge connection from pump 15 leads to the bottom of container 20 for delivery of liquid directly to the liquid phase of the container, and branch 19' leads to the upper part of container 20 for delivery to and through the gas phase. Suitable valve control means are provided for selectively apportioning the delivery through these lines as desired. This means may comprise simply manually controlled valves, such as the valves 19a and 19b, in the branches 19 and 19' respectively. Preferably, however, the selective delivery is controlled automatically. To this end branch conduit 19' has in parallel therewith a conduit 19'' having therein an automatic valve 19c. This valve may vary as to specific details, but in general is of a character to be responsive to pressure in the gas space of container 20. In operation it is arranged to open and remain open when the pressure in container 20 exceeds a predetermined value.

Under certain conditions of operation and gas consumption it may be sufficient in the recharging of container 20 merely to avoid or reduce the development of excessive pressures in container 12. In such case the entire charge may be delivered through the branch 19' into the gas phase of container 20. Assuming the liquid to be a highly volatile one, such as liquid oxygen, under the pump delivery pressure the liquid will be in a subcooled state below its boiling point temperature corresponding to such pressure and will have a refrigeration capacity which will result in lowering the temperature of the gas in container 20 and the condensation of some of the gas. Normally this will occur to the extent of lowering the pressure, despite the decreased volume of the gas space as the charging proceeds. The result will be affected, of course, by whether or not the valves 24' and 26' are closed during this operation.

Of particular advantage is the method of charging through selective delivery, by which the pressure in container 20 is maintained substantially constant, that is to say, within at least a predetermined range dependent upon the degree of constancy desired and correspondingly the care and attention given to the regulation.

The arrangement shown in Fig. 1 enables this control of the pressure during recharging to be effected manually or automatically as desired. If performed manually the shut-off valve 19d in conduit 19' preferably is closed and the liquid delivered selectively to the liquid or gas phase by manipulation of control valves 19a and 19b respectively. Delivery to the liquid phase will cause the pressure to rise, whereas delivery to the gas phase will ordinarily cause the pressure to decrease. A suitable pressure gauge, such as shown at 33, is provided to indicate the pressure and the required adjustment of the controls as the charging of container 20 proceeds. If desired the conduit 19 may be provided with a slight resistance, such as a spring pressed check valve shown diagrammatically at 19e, in which case valve 19a may be left open and the amount of delivery through conduit 19' determined by adjustment of valve 19b, the delivery being substantially all through conduit 19' when valve 19b is wide open.

For automatic control, valve 19b is completely closed and valves 19a and 19d completely open. Automatic valve 19c is set to open when the pressure in container 20 exceeds a predetermined value, as, for example, 150 lbs. per sq. inch gauge. If the pressure is below that value the delivery will be through the liquid phase line 19 until a pressure is reached above the predetermined value when valve 19c will open and delivery will then continue through the gas phase line 19' until the pressure drops sufficiently to cause valve 19c to close.

Either or both of the valves 24' and 28' may be open or closed during recharging, depending upon the character of the installation and circumstances in general. If, for example, either or both are open, any withdrawal during the recharging will contribute proportionately toward keeping the pressure down in container 20. Both valves may be closed if it is desired to isolate the container from the withdrawal system, in which case pressure control is effected entirely through the selective filling.

For most installations the main container 12 would be under low or atmospheric pressure and correspondingly of light weight economical construction, and there would be no need for, nor particular advantage in, a pressure equalization line between the two containers. A connection of that character may be provided, however, and such a one is shown in the drawing at 35 which includes a flexible coupling part 35' and appropriate shut-off valves 36 and 37. This line may conveniently connect, as shown, into a branch 31' of the pump priming line 31.

Since certain changes in carrying out the above method and in the constructions set forth, which embody the invention may be made without departing from its scope, it is intended that all matter contained in the above description or shown in the accompanying drawing shall be interpreted as illustrative and not in a limiting sense.

Having described my invention, what I claim as new and desire to secure by Letters Patent, is:

1. A method of charging under pressure a container for highly volatile liquefied gas, the delivered liquid being at a temperature below its boiling point corresponding to the delivery pressure, comprising selectively apportioning the delivery of liquid thereto between the liquid and gas phases of the container contents in amounts

such as to maintain the pressure in the container within predetermined limits.

2. A method of charging under pressure a container for highly volatile liquefied gas, the liquid at the delivery pressure being at a temperature substantially below its boiling point corresponding to such pressure, comprising selectively apportioning the delivery of the liquid between the liquid and gas phases of the container contents in amounts such as to restrict the increase in pressure resulting from the progressively reduced gas space not to exceed a predetermined value.

3. A method of charging under pressure a container with a highly volatile liquefied gas, comprising selectively delivering the liquid to the liquid and gas phases of the container contents, the amount delivered into the gas phase being controlled and made sufficient so that the refrigeration of the gaseous contents serves to prevent the development of pressure within the container during the charging operation above a predetermined limit.

4. A method of charging a closed container under pressure with a liquefied gas having a boiling point temperature below 273° K. at atmospheric pressure, comprising selectively apportioning the delivery between the liquid and gas phases of the container contents such that the amount delivered into the gas phase is sufficient by the refrigeration effect thereon to compensate for the reduced volume of gas space and to prevent a rise in pressure above a predetermined limit.

5. A method of charging a container under pressure with a highly volatile liquefied gas, the liquid at the delivery pressure being in a sub-cooled state substantially below its boiling point corresponding to such pressure, said method comprising delivering the liquid in part to the liquid phase contents of the container and in part to the gas phase contents, the latter causing a cooling and partial condensation of the gas, the respective amounts being apportioned such as to restrict the pressure rise in the container to not greater than a predetermined limit.

6. A method of charging under pressure a container with a highly volatile liquefied gas, the delivered liquid being at a temperature below its boiling point corresponding to the delivery pressure, comprising delivering the liquid in part to the liquid phase and in part into the gas phase, and apportioning the respective amounts such that the refrigeration effect on the gas compensates for the decrease in the volume of the gas space and the pressure within the container is maintained substantially constant.

7. In a system for storing and dispensing liquefied gas material, a first container, a second container, and means for delivering liquid from said first container to said second container under elevated pressure embodying conduits and controls therefor for selectively delivering the liquid to the liquid or gas phase contents of said second container in apportioned amounts to control the pressure in said second container.

8. In a system for storing and dispensing liquefied gas material, a first container, a second container, means for delivering liquid from said first container to said second container at elevated pressure, a delivery line from said means connected directly to the normal liquid phase space of said second container, a delivery line from said means connected directly to the normal gas phase space of said second container, and auto-

matic means responsive to pressure in said second container for controlling selective delivery through said lines.

9. In a system for storing and dispensing liquefied gas material, a first container, a second container adapted to maintain the material under a relatively high pressure, a pump means for delivering liquid from said first container at elevated pressure, a delivery line from said pump means connected directly to the normal liquid

10 phase space of said second container, a delivery line from said pump means connected directly to the normal gas phase space of said second container, and automatic means responsive to pressure in said second container for controlling selectively the delivery through said lines and to maintain the pressure in said second container below a predetermined value.

ODD A. HANSEN.
